United States Patent Office

Des. 222,688
Patented Nov. 30, 1971

222,688

ARCHERY CASE

Joaquin J. Canton, Riverdale, N.Y., assignor to Challenger
Mfg. Corporation, Jamaica, N.Y.

Filed Sept. 30, 1970, Ser. No. 25,281

Term of patent 14 years

Int. Cl. D3—01

U.S. Cl. D87—1

FIG. 1

FIG. 2

FIG. 1 is a front perspective view of an archery case showing my new design;

FIG. 2 is a right side elevational view of the design of FIG. 1, the left side elevational view being a mirror-image thereof;

FIG. 3 is a top plan view of the design;

FIG. 4 is a rear elevational view of the design; and
FIG. 5 is a bottom plan view of the design.

I claim:

The ornamental design for an archery case, as shown and described.
